BRUSH

Conrad Jobst, Toledo, Ohio, assignor, by mesne assignments, to The Owens Staple-Tied Brush Company, Toledo, Ohio, a corporation of Ohio

Application August 16, 1937, Serial No. 159,419

4 Claims. (Cl. 15—167)

The invention relates to brushes and more particularly to constructions designed for tooth brushes and for similar uses. It is the primary object of the invention to increase the strength, 5 rigidity and durability of the tufts. It is a further object to obtain this result even where the tuft is formed of relatively fine, or what is commonly known as soft bristles. With these and other objects in view, the invention consists in 10 the construction as hereinafter set forth.

In the drawing:

Figure 1 is a side elevation of my improved brush as designed for a tooth brush;

Figure 2 is a plan view of the brush back or 15 handle showing the arrangement of the tuft receiving bores therein;

Figure 3 is an enlarged sectional plan view of the brush on line 3—3 of Figure 4;

Figure 4 is an enlarged longitudinal section of 20 Figure 3 partly in elevation;

Figure 5 is an enlarged cross section on line 5—5 of Figure 3.

In the manufacture of tooth brushes and other brushes of a similar character it is customary 25 to secure the tufts to the brush back or handle by setting the same in spaced bores. This spacing of the tufts is desirable for sanitary reasons, but in use the outer bristles of each tuft are subjected to more severe stresses than the inner 30 bristles. As a consequence, there is a tendency for these outer bristles to break off and in time to destroy the brush. This effect is not materially changed even where the size of the bundle of 35 bristles forming the tuft is enlarged, for after the outermost bristles have been broken, those next adjacent will break in a similar manner and so on until the whole tuft is destroyed.

To overcome the defect just described I have 40 designed a construction in which a plurality of tufts are set so close to each other as to form a mutual reinforcement and to constitute in effect a single tuft. This composite tuft is then trimmed so that only the central bristles come into direct 45 contact with the work, the outer bristles being too short for engagement and constituting a resilient reinforcement for the inner bristles. Thus, a much higher degree of rigidity is imparted to the tuft even where composed of fine or soft bristles, and the length of life is also 50 greatly increased. Furthermore, the construction is one which is sanitary for each composite tuft may be suitably spaced from an adjacent composite tuft.

As shown in the enlarged views 3, 4 and 5, the 55 brush back or handle A is provided with trans-

versely extending double rows of bores B which are very close to each other and as a group form in effect an oblong substantially rectangular figure. The diameter of each bore is preferably considerably less than usual for receiving independent tufts, such for instance as .049 of an inch. Each bore has set therein a tuft C of corresponding size, preferably secured by an anchor D. The adjacent bores are so close that the tufts C bear against each other a short distance above 10 the back and form in effect a single tuft. This is subsequently trimmed to taper each of the sides toward the top, as indicated at E, F, G and H, and thus only the central bristles come in contact with the work, and these are supported 15 and reinforced by the shorter outer bristles. In fact, the construction is quite similar to that of a leaf spring in which only the long leaves directly support the load, but are indirectly supported by the shorter leaves.

In the specific construction illustrated in Figure 1 which is designed for a tooth brush, a series or group of multiple tufts I are constructed as illustrated in Figures 3, 4 and 5, and are spaced from each other longitudinally of the handle, as 25 shown. The end multiple tuft J has, in addition to the two rows, a third short row C' which is obliquely trimmed and forms an additional reinforcement for the central bristles in a direction longitudinally of the brush. Thus in use, this 30 end tuft which is subjected to greater longitudinal stresses than the others, is strengthened and stiffened for this purpose.

What I claim as my invention is:

1. A tooth brush comprising a handled back 35 provided with spaced groups of parallel bores, each group having a plurality of rows of bores extending transversely of the back, said rows and the adjacent bores in each row being in close proximity to each other, and individual tufts 40 set in the bores of each group, the outer portions thereof merging a short distance from the back to form in effect a single tuft for each group, the latter being trimmed transversely and longitudinally to press only the central bristles of the 45 group to the work, the outer bristles on all sides thereof being shorter and forming a resilient reinforcement for said central bristles.

2. A tooth brush comprising a handled back 50 provided with spaced groups of parallel bores, each group having a plurality of rows of bores extending transversely of the back, said rows and the adjacent bores in each row being in close proximity to each other, and individual tufts set 55 in the bores of each group, the outer portions

thereof merging a short distance from the back to form in effect a single tuft for each group, the latter being trimmed transversely and longitudinally to press only the central bristles of the group to the work, the outer bristles on all sides thereof being shorter and forming a resilient reinforcement for said central bristles, the end group being provided with an extra trimmed row of tufts forming an additional reinforcement 10 against longitudinal stresses.

3. A tooth brush comprising a handled back provided with spaced groups of parallel bores each group having a plurality of rows of bores extending transversely of the back, said bores being of relatively small diameter and so closely spaced that adjacent bores are substantially tangent to each other, and individual tufts set in the bores of each group the bristles thereof having relatively slight angular divergence but 15 merging with those of adjacent tufts a short distance from the back to form in effect a single tuft for each group the latter being trimmed 20

obliquely to form longer bristles resiliently reinforced by bristles which are progressively shorter toward an outer side of the tuft and the distance between the bores of one group and the adjacent bores of another group being sufficient to space 5 the tufts in the respective groups from each other.

4. A tooth brush comprising a handled back provided with spaced groups of parallel bores each group having a plurality of rows of bores 10 extending transversely of the back, said bores being of a diameter of the order of .050 of an inch and being spaced from each other by less than .015 of an inch and individual tufts set in the bores of each group the outer portions thereof 15 merging a short distance from the back to form in effect a single tuft for each group, the latter being trimmed obliquely to form long bristles resiliently reinforced by bristles which are progressively shorter bristles toward an outer side of 20 the tuft.

CONRAD JOBST.
